DESIGN FOR A COUCH BED

Joseph Martin, New York, N. Y., assignor, by mesne assignments, to United Patents, Inc., Brooklyn, N. Y., a corporation of New York

Application August 25, 1934, Serial No. 53,072

Term of patent 14 years

To all whom it may concern:

Be it known that I, Joseph Martin, a citizen of the Republic of Spain, residing in the Borough of Manhattan, city, county, and State of New York, have invented a new, original, and ornamental Design for Couch Beds, of which the following is a specification, reference being had to the accompanying drawing, forming a part thereof, in which

The figure is a perspective view of a couch bed showing my new design.

I claim:

The ornamental design for a couch bed, as shown.
